REFUSE HANDLING DEVICE

Elmer Z. Backes, Pomona, Calif., assignor, by mesne assignments, to Jimmie V. Thurmond and Effie May Thurmond, Bexar County, Tex.

Application February 17, 1955, Serial No. 488,932

4 Claims. (Cl. 214—82)

This invention relates to refuse handling devices of the type incorporating an elongated refuse collection body adapted for mounting on a motor truck chassis or the like with means arranged therein for comprising refuse as it is collected so as to increase substantially the loaded capacity of the body, and more particularly to an advantageous arrangement of accessory means within the body for facilitating the refuse compression.

Refuse collection bodies of the above noted type are disclosed in U. S. Patents No. 2,258,988, issued October 14, 1941, No. 2,557,003, issued June 12, 1951, and No. 2,696,925, issued December 14, 1954. Such bodies are characterized by an elongated form of uniform cross section, by dumping doors arranged for closing an end thereof, by a loading opening therein spaced longitudinally from the dumping doors, and by a packer member disposed transversely within the body for longitudinal movement past the loading opening to pack loaded refuse by compression against the dumping doors when closed and to discharge compressed refuse through the dumping doors when open.

The accessory means provided according to the present invention comprises a plurality of longitudinally spaced finger stays carried at the upper part of the inner face of the body between the loading opening and the dumping doors and arranged for pivoting between a normal hanging position, at which they are braced against movement away from the dumping doors, and a displaced position, at which they extend parallel with the inner face of the body in the direction of the dumping doors, so that the finger stays serve to support compressed refuse against falling away from the dumping doors when the packer member is withdrawn therefrom, while remaining displaceable to release the compressed refuse for discharge through the dumping doors.

This finger stay arrangement and other features of the present invention are described in further detail below in connection with the accompanying drawings, in which:

Fig. 1 is a side elevation, partly broken away and sectioned, of a refuse handling device incorporating an embodiment of the present invention;

Fig. 2 is a rear end view substantially as seen from the right in Fig. 1; and

Fig. 3 is an exploded view illustrating the structural arrangement of the finger stays.

In the refuse handling device shown in the drawings to illustrate an embodiment of the present invention, the elongated refuse collection body thereof, as mentioned above, is indicated generally by the reference numeral 10, with dumping doors 11 arranged to close its rear end and side doors provided at 12 to form a loading opening therein spaced longitudinally from the dumping doors 11 toward the forward body end. Inside the body 10, a packer member or compressor plate 13 is disposed transversely for longitudinal movement past the loading opening at the side doors 12 to compress loaded refuse against the dumping doors 11 when closed, as well as to discharge the compressed refuse through dumping doors 11 when open. Longitudinal movement of the packer member 13

2

is provided for through means such as a sprocket chain connection, as at 14, extended between an idler sprocket at 15 and a winch at 16 to pull the packer member 13 longitudinally in either direction within the body 10.

Power for driving the winch 16 to move the packer member 13 longitudinally in this manner may be supplied by a suitable drive train from the motor of a motor truck 17 on which the body 10 is mounted as illustrated in Fig. 1, and as is disclosed in further detail in the above noted

10 prior patents.

It will be noted that the packer member 13 is arranged so that its bottom portion curves or projects towards the dumping doors 11. The purpose of this arrangement of the packer member is to exert a lifting action on refuse as it is compressed against the dumping doors 11 and thereby raise the refuse during compression so that it is packed throughout the cross section of the body 10. During the loading of the body 10 with collected refuse several successive compressions are necessary to clear the loading opening periodically for receiving additional refuse as it is collected, and the packer member 13 is accordingly operated to compress the collected refuse in successive batches toward the dumping doors 11, which means that the packer member must be withdrawn after compressing each batch of refuse to prepare for compression of a succeeding batch. Upon this withdrawal of the packer member 13 from a compressed batch of refuse there is a tendency for the topmost part of the compressed batch, which has been raised upwardly in the body 10 by the lifting action of the packer member 13, to topple over forwardly or fall away from the dumping doors 11 and thereby lose its packed arrangement, as well as render more difficult the succeeding compression. According to the present invention this complication is

35 eliminated by providing an arrangement of finger stays 18 within the body 10 to support the top portion of succeeding refuse batches as they are compressed so as to maintain the fully packed arrangement of each batch as the packer member 13 is withdrawn therefrom.

40 The finger stays 18 are carried at the upper part of the near face of the body 10 with a longitudinally spaced arrangement between the loading opening at the side doors 12 and the dumping doors 11. The spacing of the

45 finger stays 18 should start closely adjacent the loading opening so as to provide support especially for the last of the succeeding refuse batches that are compressed, and should extend for a major portion of the length of the body 10 toward the dumping doors 11, although it is not necessary to provide the finger stays 18 closely adjacent the dumping doors 11 because less difficulty is encountered with toppling over of the first of the compressed refuse batches, as the first batch compressions are carried out directly against the dumping doors 11, or with

50 a relatively small amount of previously compressed refuse interposed, so that a more secure packing of the refuse is obtained during such compressions. Also, it is easier to recompress any part of an early batch that topples over, due to the smaller total amount of compressed refuse being dealt with.

An effective arrangement of the finger stays 18 consists of three longitudinal rows thereof with a center row positioned centrally at the top of the body 10 and one row spaced at each side thereof, as shown in the drawings. The finger stays 18 are suitably formed of steel straps or bars, and they are conveniently mounted within the body 10 on hangers formed by a top plate 19 secured at the inner face of the body 10 by welding, or in any other effective manner, and carrying spaced side plates 65 20 between which the finger stays 18 may be assembled on pivot pins 21. An end plate 22 is preferably arranged in covering relation at the front ends of the top and side

plates 19 and 20 so as to prevent clogging of these finger stay hangers with refuse. The end plate 22 is illustrated in the drawings with a vertical disposition, although it may be desirable in some cases to arrange it angled downwardly toward the dumping doors 11 so that any abutting refuse will be directed downwardly thereunder during compression without any tendency to jam the packer plate 13.

The finger stays 18 are mounted on the pivot pins 21 at the radial center of a rounded end corner 23 thereof, and this rounded corner is disposed toward the dumping doors 11 in mounting the finger stays 18 so that they hang normally within the body 10 with the adjacent end face 24 thereof arranged for opposing abutment with the inner face of the hanger top plate 19 to brace the hanging finger stays 18 against pivoting movement away from the dumping doors 11; while leaving them free for pivoting movement between this normal hanging position and a displaced position, at which they are folded between the hanger side plates 20 to extend parallel with the inner face of the body 10 in the direction of the dumping doors 11. In order to arrange the finger stays 18 for bracing to the best advantage at their hanging position, the adjacent end face thereof may be angled so that the angle α formed thereby with the adjacent finger stay side edge 25 is sufficiently less than a right angle to dispose the end face 24 at a position bearing against the inner face of the hanger top plate 19 when the finger stay 18 is hanging from its pivot axis. Because the pivot axis of each finger stay 18 is located at the rounded corner 23, the finger stays 18 tend to hang normally at a position inclined toward the dumping doors 11 which improves their action in supporting the compressed refuse, and angle α may be further proportioned to increase this inclination if desired.

The pack member 13, being normally arranged with a working face coextensive transversely with the cross section of the body 10, is slotted according to the present invention as shown at 26 to clear the finger stays 18 during its longitudinal movement, and the result of this arrangement is to allow operation of the packer member 13 in the usual manner for compressing successive batches of refuse within the body 10, while providing the normally hanging finger stays 18 to support the compressed refuse so that its fully packed arrangement is maintained in the body 10 as the packer member is successively withdrawn from each compressed batch. After the body 10 is completely loaded with compressed refuse, and is ready for unloading, the action of the packer member 13 in discharging the compressed refuse through the opened dumping doors 11 results in pivoting the finger stays 18 to their displaced position so that they release the compressed refuse for discharge without any interference whatever.

The present invention has been described in detail above for purposes of illustration only and is not intended to be limited by this description or otherwise except as defined in the appended claims.

I claim:

1. A refuse handling device comprising an elongated body arranged for mounting on a motor truck chassis or the like, said body being of uniform transverse cross section throughout its length, having an end thereof closed by dumping doors, and having a loading opening therein spaced longitudinally from said dumping doors, a packer member arranged transversely within said body for longitudinal movement to compress against said dumping doors refuse loaded therein through said loading opening, and a plurality of finger stays spaced longitudinally in said body from a point adjacent said loading opening toward said dumping doors, said finger stays being pivoted so as normally to hang from one end within said body at the top thereof for supporting compressed refuse from falling away from said dumping doors while being foldable against the adjacent top side face of said body in the

direction of said dumping doors to release said compressed refuse for discharge through said dumping doors, and said packer member being slotted for clearing said finger stays during longitudinal movement thereof.

2. A refuse handling device comprising an elongated body arranged for mounting on a motor truck chassis or the like, said body being of uniform transverse cross section throughout its length, having an end thereof closed by dumping doors, and having a loading opening therein spaced longitudinally from said dumping doors, a packer member arranged transversely within said body for longitudinal movement past said opening to compress refuse loaded therein against said dumping doors when closed and to discharge compressed refuse through said dumping doors when open, and a plurality of longitudinally spaced finger stays pivotally mounted adjacent the top of said body to hang normally therein between said loading opening and dumping doors, said finger stays being pivotally mounted at the radial center of a rounded end corner thereof that is disposed toward said dumping doors so that when hanging normally any substantial pivoting of said finger stays away from said dumping doors is prevented by abutment of the end faces thereof at the inner face of said body while said finger stays remain pivotable to fold against the adjacent inner face of said body when forced in the direction of said dumping doors, said packer member being slotted for clearing said finger stays during longitudinal movement thereof, and said finger stays serving to support compressed refuse against falling away from said dumping doors when said packer member is withdrawn therefrom while being yieldable to release said compressed refuse for discharge through said dumping doors.

3. A refuse handling device as defined in claim 2 and further characterized in that at the rounded end corner of said finger stays the adjacent finger stay end face is angled at less than a right angle with respect to the adjacent finger stay side edge, whereby said finger stays hang normally with said adjacent end faces abutting the inner face of said body and with an inclination directed toward said dumping doors.

4. In a refuse handling device of the type incorporating an elongated body having a uniform cross section with dumping doors closing an end thereof, a loading opening therein spaced longitudinally from said dumping doors, and a packer member arranged transversely within said body for longitudinal movement past said opening to pack loaded refuse throughout the cross section of said body by compression against said dumping doors when closed and to discharge compressed refuse through said dumping doors when open, the improvement comprising a plurality of longitudinally spaced finger stays carried at the upper part of the inner face of said body between said loading opening and said dumping doors, said packer member being slotted for clearing said finger stays during longitudinal movement thereof, and said finger stays each being mounted adjacent one end for pivoting between a normal hanging position at which they are braced against movement away from said dumping doors and a displaced position at which they extend parallel with the inner face of said body in the direction of said dumping doors so that said finger stays serve to support compressed refuse against falling away from said dumping doors when said packer member is withdrawn therefrom while remaining displaceable to release said compressed refuse for discharge through said dumping doors.
